CLAIM

The ornamental design for a laundry treating appliance, as shown and described.

DESCRIPTION

FIG. 1 is a top perspective view of a laundry treating appliance showing our new design;

FIG. 2 is a top view of the laundry treating appliance of FIG. 1;

FIG. 3 is a front view of the laundry treating appliance of FIG. 1;

FIG. 4 is a left side view of the laundry treating appliance of FIG. 1; and,

FIG. 5 is a right side view of the laundry treating appliance of FIG. 1.

Portions of the drawings shown in broken lines illustrate portions of the laundry treating appliance that form no part of the claimed design.

1 Claim, 5 Drawing Sheets
